[57] CLAIM

The ornamental design for an illuminable note paper tray, as shown and described.

DESCRIPTION

FIG. 1 is a perspective view of an illuminable note paper tray showing my new design;

FIG. 2 is a front elevational view thereof;

FIG. 3 is a rear elevational view thereof;

FIG. 4 is a top plan view thereof, the writing instrument shown in broken lines being for illustrative purposes only;

FIG. 5 is a bottom plan view thereof; and

FIG. 6 is a right side elevational view thereof.
